Primary Examiner — Stella Reid*Assistant Examiner* — Holly E Thurman(74) *Attorney, Agent, or Firm* — Harness, Dickey & Pierce(57) **CLAIM**

The ornamental design for a microphone for digital camera, as shown and described.

DESCRIPTION

FIG. 1 is a front/right-side/top perspective view of a microphone for digital camera showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The broken line portion of the figure drawings depicts unclaimed subject matter only and forms no part of the claimed design.
